SERVING TRAY

Clifford C. Towns, Richmond Heights, Mo., assignor to Seeo Company, Inc., St. Louis, Mo., a corporation of Missouri

Application July 3, 1953, Serial No. 25,796

Term of patent 14 years

(Cl. D44—10)

To all whom it may concern:

Be it known that I, Clifford C. Towns, a citizen of the United States and a resident of Richmond Heights, county of St. Louis, State of Missouri, have invented a new, original, and ornamental Design for a Serving Tray, of which the following is a specification, reference being had to the accompanying drawing, forming a part thereof.

Fig. 1 is a top plan view of a serving tray embodying my new design.

Fig. 2 is an elevational view in cross-section taken on the line 2—2 in Fig. 1, and

Fig. 3 is a fragmentary cross-sectional view taken at line 3—3 in Fig. 1.

I claim:

The ornamental design for a serving tray, substantially as shown.

CLIFFORD C. TOWNS.
